UNITED STATES PATENT OFFICE.

FRANK L. SESSIONS, OF LAKWOOD, OHIO.

SPARK-PLUG.

1,228,487.

Specification of Letters Patent. Patented June 5, 1917.

Application filed May 8, 1915. Serial No. 26,763.

To all whom it may concern:

Be it known that I, FRANK L. SESSIONS, a citizen of the United States, residing at Lakewood, in the county of Cuyahoga and 5 State of Ohio, have invented certain new and useful Improvements in Spark-Plugs, of which the following is a specification.

My invention relates to improvements in electric spark plugs, such as are used for 10 igniting explosive mixtures of fuel and air in internal combustion engines, and has for its object the provision of a simple, cheap, and readily manufactured spark plug having a ground terminal combined with a 15 packing washer for the porcelain or other insulating material which supports the insulated electrode, and possessing advantages over existing types of spark plugs which will be apparent from these specifications.

20 A further object of my invention is the provision of means whereby the ground terminal may be readily and quickly removed from the supporting metal shell for inspection and cleaning, and replaced with 25 assurance that the length of the spark gap has not been altered.

A further object of my invention is to provide a spark plug, from which the porcelain or other insulating material which 30 supports the insulated electrode may be easily withdrawn and cleaned and again returned to its place without changing the length of the spark gap.

I have found that the insulated electrode 35 frequently becomes short circuited to the metal shell surrounding it by a thin but continuous layer of carbon extending over the surface of the insulating material from the insulated electrode to the metal shell which 40 is screwed into the wall of the cylinder or combustion chamber. In most instances this layer of carbon can be easily wiped or scraped off from the insulation and the spark plug is thereby made perfectly operative again. Existing spark plugs are so 45 constructed that either it is difficult or impossible to remove the insulation for cleaning, or when it has been so removed, cleaned, and replaced, the length of the spark gap 50 is not the same as it was before. Some of the present forms of spark plugs are designed so that the porcelain members may be removed and cleaned without removing the metal shell from the cylinder, but in 55 those spark plugs with which I am familiar

it is impossible to examine the normally grounded sparking point without removing the above mentioned metal shell; or, auxiliary metal shells are used which are secured to the insulation in a permanent manner, making cleaning, inspection and packing very difficult. In such spark plugs, when the porcelain is again returned to its seat, especially if a new packing washer be employed to make a fluid tight joint, the 60 length of the spark gap is frequently changed, making it necessary to adjust it in order to secure proper ignition. Other spark plugs have been designed to overcome some of these objections, but they are composed of many parts which are difficult to manipulate. 70

By the use of my improvements, the inspection and care of this important adjunct to the internal combustion engine is readily 75 given by even unskilled persons, and much time trouble and expense are thereby saved. By my construction it is possible to make the combined ground terminal and packing washers perfectly interchangeable, so that 80 the replacement of an old by a new one does not materially alter the length of the spark gap. The length of the spark gap of my improved spark plug may, however, be adjusted as readily as that in any of the existing 85 types with which I am familiar.

The particular means and their functions employed in carrying out the objects of my invention are fully described in these specifications and claims and shown in the accompanying drawings in which Figure 1 is a longitudinal section through a preferred form of spark plug embodying my improvements; Fig. 2 is a plan, and Fig. 3 is a longitudinal section of the combined ground terminal and packing washer used in the spark plug shown in Fig. 1; Fig. 4 is a longitudinal section through another form of spark plug embodying a modification of my improvements; Figs. 5 and 6, are respectively plan and longitudinal section of the ground terminal and packing washer shown in Fig. 4; Figs. 7 and 8 are respectively plan and longitudinal section of a different form of my improved combination ground 95 terminal and packing washer in which there are shown variations in the sparking point and packing washer; Fig. 9 is a longitudinal section of a spark plug using the form of ground terminal and packing washer 100 105 110

shown in Figs. 7 and 8, together with an additional packing washer of well known form; Fig. 10 is a longitudinal partial section on an enlarged scale, of the packing washers shown in Fig. 9.

It will be understood that these and other modifications of my invention may be made without departing from its scope. For instance, the sparking point on the ground terminal may be formed in a number of ways, either by bending in a portion of the metal wall of the ground terminal; or by attaching to it a wire of suitable material; or by simply leaving the wall of the ground terminal in its circular cross sectional form with an open bottom end, and by bringing the insulated sparking point into proper proximity to form the desired length of spark gap.

20 Referring to the drawings, 1 represents the exterior metal shell or body of a spark plug, having its lower end threaded and screwed into the metal wall, 2, of an internal combustion engine cylinder. 3 is a metal cap threaded internally and screwed onto the correspondingly externally threaded upper end of the shell, 1. The cap, 3, is provided with an inturned shoulder or flange, 4, for clamping the insulation, 5, preferably 25 made of porcelain, firmly in place. 6 represents the combined ground terminal and packing washer. As shown in Figs. 1, 2, and 3, it has the form of a hollow, thin walled metal cylinder or thimble, having a 30 practically straight body portion, 7, a rounded bottom, 8, and an outwardly turned flange, 9, at the top end. The flange, 9, is shown turned over a cushioning washer, 10, of asbestos or other yielding material suit- 35 able for the purpose, in order that the comparatively thin and soft metal of the flange, 9, may conform to any slight irregularities in the surfaces of the insulation, 5, and the metal shell, 1, between which the flange, 9, 40 is clamped so as to make fluid tight joints therewith.

It will be observed that aside from the slight yielding of the metal of the top surface of the flange, 9, as it is clamped in 50 place between the insulation, 5, and the shell 1, there will be no change in the length of the spark gap due to the yielding of the cushioning washer, as both the insulated and the grounded spark points will move in 55 unison in response to such yielding of the cushioning washer, as will be apparent from the further description of these parts.

I prefer to make the body portion, 7, of the ground terminal, 6, larger in diameter 60 than the insulation which it surrounds, in order that any carbon which may accumulate on their opposed surfaces may not form a short circuit between the electrodes. I have found that the length of time a spark 65 plug may be operated without cleaning is

about proportional to the distance between the insulated electrode and the normally grounded electrode as measured on the surface of the intervening insulation. It is therefore desirable to leave a clearance space 70 between the insulation and the grounded electrode so that carbon deposits may not effect a virtual shortening of this surface distance. The ground terminal, 6, may be made to fit somewhat loosely in the bore of 75 the shell, 1, as electrical contact between these members is insured by the clamping of the flange, 9, against the end of shell, 1.

11 represents the sparking terminal of the insulated electrode, 12. This insulated electrode passes through and is sealed into the insulation, 5, in the usual manner, and is provided at its protruding outer end with a threaded portion 12^a, on which are the customary means such as the nut, 13, and jam 80 nut, 14, for making connections to the electric circuit. 15 is a metal cushioning washer between the insulation, 5, and the shoulder, 4, of the cap, 3. When a modified form of my combined ground terminal and packing 85 washer, to be presently described, is used, the washer, 15, may be dispensed with.

16 is a sparking point upon the ground terminal or electrode, 6. As shown in Figs. 1, 2, and 3, it is formed by making a sharp 90 inwardly projecting depression in the metal at the axial center of the rounded bottom, 8. It may, however, be formed in any other desirable or convenient way, as for instance, by riveting a short piece of wire of nickel, platinum, or other suitable material, to the 95 rounded bottom, 8, as will be understood by those skilled in the art.

17, 17 are holes in the wall of the ground terminal, 6, to admit the explosive mixture 100 to the spark gap. These holes may be of any convenient or desirable size or shape, and may even extend upward along the body portion, 7, of the ground terminal, 6, close to the line where the flange, 9, is formed.

In Fig. 4 I have shown a spark plug fitted with a modified form of my improvement, which is adaptable to certain designs of spark plugs now in use.

In order to show the adaptability of this 115 construction, I have preferred to omit the metal body or shell which is customarily screwed into the wall of the explosive chamber, and show instead, in Fig. 4, the insulated electrode with its insulation and a 120 modified form of my combined ground terminal and packing washer supported in a counterbored hole formed directly in the wall of the explosion chamber. If desired, a metal body or shell of usual construction 125 may be employed, and, in the usual construction of spark plugs with which I am familiar, it is necessary to employ such a member because it forms the ground terminal which carries the normally grounded 130

sparkling point. By the use of my improvement, the metal body or shell may be dispensed with as shown in Fig. 4.

In Fig. 4, 18 represents the wall of the explosion chamber or cylinder of an internal combustion engine, and 19 is a hole through the wall, 18. This hole is enlarged by counter boring from the outer surface of the wall, 18, as shown at 20, part way through the wall, 18. A shoulder, 21, is thus formed in the metal surrounding the hole, 19. The counterbored portion, 20, of the hole, 19, is internally threaded to receive a correspondingly threaded clamping member, 22.

15 The insulation, 23, which carries the insulated electrode, 24, is formed similar to part 5 shown in Fig. 1, except that in order to maintain the necessary distance between the clamping member, 22, and the exposed, 20 insulated electrode connections at the top of the insulation, the length of the insulation, 23, from the shoulder, 24^a, to the top end is made greater than the corresponding portion of the insulation, 5, shown in Fig. 1.

25 The combined ground terminal and packing washer which I prefer to use in connection with the spark plug shown in Fig. 4 consists, as in the form shown in Fig. 1, of a metal cylinder or thimble, 25, having a practically straight body portion, 26. It, also, has an outwardly turned flange, 27, at the top of the body portion, 26. Instead of terminating at this flange, however, the metal is continued above it in the form of an enlarged cylinder, 28, which extends to the shoulder, 24^a, of the insulation, 23, and is there inturned to form a second flange, 29, the purposes of which are to form a metal cushion between the end of the clamping 30 member, 22, and the shoulder, 24^a, of the insulation, 23, and further to form a means coöperating with the shoulder, 24^a, for withdrawing the member, 25, with the insulation, 23, when it is desired to inspect or change 35 the spark plug.

In order to permit the flange, 29, to pass over the enlarged portion of the insulation, 23, below the shoulder, 24, I prefer to cut the metal of the flange, 29, and the enlarged cylinder, 28, longitudinally, as shown by the slots, 30, 30, thus forming outwardly yielding fingers, 30^a, 30^a. After the insulation, 23, has been inserted into member, 25, these fingers close in and the flange, 29, 40 overlaps the shoulder, 24^a, for the purposes set forth. If desired, the slots, 30, 30, may be omitted, and the member, 25, be secured to the insulation by forming the flange, 29, after the insulation, 23, has been inserted 45 into the ground terminal, 25. Such a construction, however, makes it difficult to clean the insulation without deforming the ground terminal, and I prefer to employ the slotted form shown.

50 In Figs. 7 and 8, a modified form 31, of

my improved ground terminal and packing washer is shown. In this form there is the straight cylindrical portion, 32, but the top end is simply flared outwardly to form the flange, 33, and is not inturned as is the flange 55 of the ground terminal shown in Figs. 1, 2 and 3, not turned upward to form an enlarged cylindrical body portion as shown in Figs. 4, 5 and 6. The sparkling point, 34, of the ground terminal, 31, shown in Figs. 7, 8 and 9, is formed out of the metal of the bottom part of the straight cylindrical portion. Transverse slits or holes, 35, extending part way around the circumference, are cut in the wall of the cylinder near the bottom end 60 so as to leave transverse bars, 36, extending between the intervening portions of the wall. Sparking points, 34, may be formed at the centers of these strips, 36, and the strips be bent inwardly until the sparkling points 65 stand approximately in the center of the cylinder, directly under the sparkling point of the insulated electrode when the spark plug is assembled. In this construction, the ground terminal must be made of material 70 suitable for use as sparking points, or the sparking points must be separately made of suitable material and attached to the strips, 36.

In Fig. 9 is shown a spark plug in which 75 a ground terminal and packing washer such as is shown in Figs. 7 and 8 is used. In addition to the flange, 33, however, there is shown in this arrangement, an additional washer, 37, of yielding material, such as is 80 commonly used in spark-plug construction. In Fig. 10 is shown an enlarged partial section through this packing washer arrangement.

When the opposed surfaces of the shoulder, 38, on the insulation, 5, and the shoulder, 39, in the metal wall of the hole, 40, in which the spark plug elements are assembled, are true and smooth, the comparatively soft metal of which the combined 85 ground terminal and packing washer is made is sufficient packing to make fluid tight joints, but when necessary, the additional washer, 37, of yielding material may be used. It is to be noted particularly that the 90 use of such an additional washer does not materially affect the length of the spark gap.

The combined ground terminal and packing washer may be made of any metal or other 95 conducting material found suitable. It may be formed by pressing or drawing it from sheet metal; or, it may be formed from metal tubing; or, in any of the various other ways well known to metal workers and found convenient or desirable. It may be made of copper or of German silver and the sparkling point be made of the same metal, or of iron, nickel, platinum or any other suitable 100 metal.

I claim as my invention:

1. In a spark plug, insulation surrounding and carrying the inner electrode, the insulation having an enlarged portion forming inner and outer transverse shoulders, a metal shell adapted to be secured in the wall of the combustion chamber which the spark plug serves, a ground terminal provided with a 5 sparking point at its inner end and an outwardly turned, transverse flange at its outer end, the body portion of the ground terminal being adapted to enter the bore of the metal shell, and the flange of the ground terminal being adapted to rest on the outer end of the metal shell, and means coöperating with the insulation and the metal shell to clamp the flange of the ground terminal between the inner shoulder on the insulation and the metal shell.
  2. A ground terminal for spark plugs, having a tubular body portion provided at its inner end with a sparking point and at its outer end with an outwardly projecting transverse flange adapted to serve as a packing washer for the insulation which surrounds and carries the inner electrode, said flange being formed by first outwardly flaring the end metal of the tubular body portion and then undercutting the outer portion of the flange thus formed and including a washer of yielding material between the upper, outwardly flared portion and the lower, undercut portion.
  3. A ground terminal for spark plugs, having a tubular body portion provided with a sparking point at its inner end, an outwardly turned transverse flange at its outer end, a tubular extension to the outwardly turned transverse flange, an inwardly turned transverse flange at the outer end of the tubular extension, said outwardly turned transverse flange being adapted to serve as a packing washer between a shoulder on the insulation which surrounds and carries the inner electrode and a shoulder on the wall of the supporting member, and the inwardly turned transverse flange being adapted to serve as a cushioning washer between a shoulder on said insulation and the member which clamps it to the supporting member and to serve as a means for withdrawing the ground terminal with the insulation from the supporting member.
  4. A ground terminal for spark plugs,
- having a tubular body portion provided 55 with a sparking point at its inner end, an outwardly turned transverse flange at its outer end, a tubular extension to the outwardly turned transverse flange, an inwardly turned transverse flange at the outer 60 end of the tubular extension, said outwardly turned transverse flange being adapted to serve as a packing washer between a shoulder on the insulation which surrounds and carries the inner electrode and a shoulder 65 on the wall of the supporting member, and the inwardly turned transverse flange being adapted to serve as a cushioning washer between a shoulder on said insulation and the member which clamps it to the supporting 70 member and to serve as a means for withdrawing the ground terminal with the insulation from the supporting member, the tubular extension and the inwardly turned transverse flange being split longitudinally 75 to permit the shoulders on the insulation to enter the tubular extension.
5. In a spark plug adapted to be secured in the opening in the wall of the combustion chamber which the spark plug serves, an insulation body surrounding and carrying the inner electrode and having an annular shoulder, a ground terminal carrying a 80 sparking point at its inner end and an annular flange at its outer end, a tubular member carried by the combustion chamber and provided with an annular shoulder, a compressible washer between said annular shoulder and said annular flange on the ground terminal, and means for clamping said 85 washer against said shoulder through the medium of said annular flange and the shoulder on the insulation body, the washer coming in direct contact with the shoulder carried by the combustion chamber and the 90 annular flange on the ground terminal coming in direct contact with the shoulder of the insulation body, whereby the compression of the washer in clamping the parts in position will not vary the distance between 95 the spark points.
- In testimony whereof I affix my signature in presence of two witnesses.

FRANK L. SESSIONS.
